UNITED STATES PATENT OFFICE.

JESSE EMANUEL PRICE, OF RUTH, MISSISSIPPI.

NUT-LOCK.

SPECIFICATION forming part of Letters Patent No. 625,122, dated May 16, 1899.

Application filed August 16, 1898. Serial No. 688,722. (No model.)

To all whom it may concern:

Be it known that I, JESSE EMANUEL PRICE, a citizen of the United States, residing at Ruth, in the county of Lincoln and State of Mississippi, have invented certain new and useful Improvements in Nut-Locks; and I do hereby declare the following to be a full, clear, and exact description of the invention, such as will enable others skilled in the art to which it applies to make and use the same.

This invention relates to a useful and new improvement in nut-locks; and it consists in the invention hereinafter disclosed.

Referring to the drawings, Figure 1 represents a perspective view of the device with the keeper closed. Fig. 2 represents a similar view with the keeper open. Fig. 3 represents a transverse section.

In the drawings the letters A A' represent the meeting ends of two railroad-rails provided with the fish-plates B B', through which the rails pass the ordinary bolts C, having the nuts c. To one end of the fish-plate B is hinged one end of the keeper D, the latter having the angular opening or aperture d, corresponding in size and shape with the nuts c. At its free end d' the keeper D is made with an angular notch d² and has below said notch the right-angular offset d³ and the stop d⁴ spaced apart from the offset d³. This stop d⁴ has the incline d⁵ on top and a perpendicular wall d⁶ toward the offset d³. Hinged to the fish-plate B is the latch E, bent at e so that its two parts e' and e² are out of line, as shown. This latch E is so secured or located upon the fish-plate B that it will align with the notch d² when the keeper D is closed against the fish-plate B. After the bolts and nuts are put in

place the keeper D is sprung against the fish-plate B, the apertures d coming over the nuts c, effectually preventing their accidental dislodgment. The latch E comes into the notch d² and is then turned around its pivot until it is pushed over the incline d⁵ and drops down between the offset d³ and the stop d⁴. The offset d³ extends out from the face of the keeper D so far that the latch E cannot be turned past it; but said latch has to be turned around and over the stop d⁴, and, coming up against the offset d³, cannot go any farther. This is due to the fact that such offset d³ is greater in length than the depth of the main portion of the latch E and so much greater that such latch cannot be passed over offset d³. While in this position any accidental loosening is effectually prevented, and the part e² of the latch E lies against the base of the rail and is used as a handle when it is desired to open the keeper, so as to get at the fish-plate.

Having described my invention, what I claim is—

The combination of the fish-plate, B, having the latch, E, bent at e so that its two parts, e' and e², are out of line at one end with the keeper, D, hinged at the other end of such fish-plate, such keeper having the angular opening, d, the notch, d², the angular offset, d³, and stop, d⁴, below such notch, as set forth.

In testimony whereof I affix my signature in presence of two witnesses.

JESSE EMANUEL PRICE.
